UNITED STATES PATENT OFFICE.

JOHN WATERFIELD, OF PROVIDENCE, RHODE ISLAND, ASSIGNEE, BY MESNE ASSIGNMENTS, TO SHANNOCK NARROW FABRIC COMPANY, OF PAWTUCKET, RHODE ISLAND, A CORPORATION OF RHODE ISLAND.

KNITTING-MACHINE.

1,285,505.

Specification of Letters Patent. Patented Nov. 19, 1918.

Application filed January 20, 1915. Serial No. 3,195.

To all whom it may concern:

Be it known that I, JOHN WATERFIELD, a citizen of the United States, residing at the city of Providence, in the county of Providence and State of Rhode Island, have invented new and useful Improvements in Knitting-Machines, of which the following is a specification.

This invention relates to knitting machines for the manufacture of tubular braids, tapes and other similar fabrics, and the object thereof is to provide a machine which will produce a plurality of such fabrics at the same time and in which the width of these fabrics may be varied at will.

My improved knitting machine is characterized by the combination of two straight rows of needles, arranged parallel to each other, capable of a limited vertical movement and also a limited lateral movement in opposite directions, the fabric being knitted on each row of needles independently of the other row; mechanism for connecting the ends of these rows together to form the complete fabric; mechanism for tightening the loops immediately after the formation thereof, and automatic stop motion devices adapted to stop the operation of the machine whenever the breakage of thread occurs.

In the accompanying drawings forming a part of this application, Figure 1 is a front elevation of my knitting machine, partly broken away;

Fig. 2 is a side elevation of Fig. 1;

Fig. 3 is a section on the line 3—3, Fig. 6, showing the stitch-tightening device and its operating parts;

Fig. 4 is a section on the line 4—4, Fig. 1;

Fig. 5 is a central vertical section of the stitch-tightening devices and the take-up rolls;

Fig. 6 is a section on the line 6—6, Fig. 1, showing the front cam shaft and the cam for operating the needle bar vertically and the rear cam shaft and its cam which operates the end thread guides;

Fig. 7 is a central vertical section through the knitting mechanism, the thread guides, the stitch tightener and the stop motion on an enlarged scale;

Fig. 8 is a side elevation of one pair each

of side and end thread guides and a fragment of the needle bars with the guides in their closed position;

Fig. 9 is a view similar to Fig. 8 with the guides in their open position, and the end guides omitted;

Fig. 10 is a detailed elevation of the end thread guides in one position;

Fig. 11 is a similar view to Fig. 10 with the guides in another position;

Fig. 12 is a section on the line 12—12, Fig. 13;

Fig. 12^a is a section on the line 12—12, Fig. 13;

Fig. 13 is a side elevation of Fig. 12;

Fig. 14 is a diagrammatic view of the movements of the thread guides;

Fig. 15 is a diagrammatic illustration of the loops upon the needles as laid by the thread carriers.

In the drawings 1 is a bench or table supported at the desired height by standards 2 upon which is supported a bed plate 3 by standards 4 and 5. Two shafts 6 and 7 are rotatably mounted in standards 4 and 5. Upon one end of shaft 6 are mounted two pulleys 8 and 9, one of which, 8, is loose, and the other, 9, is tight. A gear 10 is fastened upon the end of shaft 6 near the pulleys and meshes with a gear 11 secured upon the end of shaft 7, gear 10 being provided with twice as many teeth as gear 11 so that shaft 6 will rotate twice as fast as shaft 7. Secured upon shaft 6 near the center thereof are two needle-lifting cams 12 and 13, said cams being provided with cam shoes 14 and 15 in the upper ends of which are mounted the lower ends of the needle-lifting rods 16 and 17. The shaft 6 also has secured thereon adjacent to the inner sides of the standards 4 and 5 two thread-guide-operating cams 18 and 19 which operate the side thread guides and are provided with cam shoes 20 and 21 to the upper ends of which are secured the lower ends of push rods 22 and 23. A stitch-tightening cam 24 is secured upon the end of the shaft 6 adjacent the outer side of the standard 4 and is provided with a shoe 25 from one end of which extends the stitch-tightener-operating rod 26.

Mounted upon the rear shaft 7 near the inner sides of the standards 4 and 5 are two

needle-lifting cams 27 and 28, said cams being provided with cam shoes 29 and 30 in the upper ends of which are mounted the lower ends of the needle-lifting rods 31 and 32. The shaft 7 also has secured thereon adjacent to the inner sides of the standards 4 and 5 two thread-guide-operating cams 33 and 34 which operate the side thread guides and are provided with cam shoes 35 and 36 to the upper ends of which are secured the lower ends of push rods 37 and 38. A stitch-tightening cam 39 is secured upon the end of the shaft 7 adjacent the outer side of the standard 5 and is provided with a shoe 40 from one end of which extends the stitch-tightener-operating rod 41.

Mounted upon the rear shaft 7 near the inner sides of the standards 4 and 5 are two

end thread-guide-operating cams 27 and 28 and cam shoes 29 and 30 ride upon said cams. Push rods 31 and 32 extend upwardly from said shoes and operate said end 5 thread guides.

Secured upon the left-hand end of the shaft 7 is a cam 33 which imparts a horizontal reciprocating movement to the needle bars.

10 A bracket 34 extends up from the top of the bed plate 3 and has a bearing in which is pivotally mounted a rocker arm 35, the lower end of which rocker arm is bifurcated and straddles the cam 33, so that as the cam 15 33 rotates, the upper end of the arm 35 will be rocked longitudinally.

The stitch-tightening device is operated by a cam 24 on the shaft 6 which cam gives a reciprocating movement to the shoe 25 20 which is communicated to the rock arm 36 by the rod 26.

The rock arm 36 is rigidly mounted upon a rod 37 secured in standards 4 and 5 parallel to the shafts and upon the outer end 25 thereof and extends downwardly therefrom. Rigidly mounted upon the rod 37 between the inner sides of the standards 4 and 5 are two upwardly-extending rock arms 38 and 39, to the upper ends of which are pivotally 30 secured the inner ends of a U-shaped pulling rod 40. Immediately below the opening 41 in the bed plate 3 are two spaced fixed parallel rods 42 and 43 mounted one above the other in the standards 4 and 5 between 35 which last rods the pulling rod 40 is adapted to be moved. Two grooved pulleys 44 and 45 are loosely mounted upon the rod 37 and a similar pulley 46 is secured upon the shaft 6 at the side of the cam 13 around which 40 last pulley is passed a band 47 which in turn passes over pulleys 44 and 45 and then extends downwardly and passes around a pulley 48. The pulley 48 is mounted upon one end of a shaft 49 mounted in bearings 45 upon the table 1, which shaft has secured thereon a worm 50, which worm meshes with a worm gear 52 mounted upon one end of a take-up roll 53. The roll 53 is mounted in the frame 54 mounted upon said table, 50 and a similar roll 55 is mounted therein at the side of the roll 53. The other ends of 55 these rolls are connected by gears 56 and 57 so that they move together.

Extending upwardly from the top of the 55 bed plate 3 centrally thereof are two standards 58 and 59 which are provided near their lower ends with slots 60 and 61 in which are slidably mounted the needle plates 62 and 63. Suitable mechanism is provided for reciprocating the needle plates 62, 63 simultaneously but in opposite directions. In the construction herein shown the front needle plate 62 is provided at one end with a projecting arm 64 to which is 65 pivotally connected the upper end of the

rocker arm 35 of the cam 33. The needle plate 62 has an L-shaped bracket 65 rigidly secured thereto, and the lower leg of said bracket is provided with a slot 165 in which is received a pin 166 rigidly carried by one 70 end of a rocking lever 66 that is pivotally mounted centrally upon the stud 67 mounted in the top of the bed plate 3. The rear needle plate 63 has a similar bracket 68 rigidly secured thereto which is also provided with a slot 168 that receives a pin 169 secured in the opposite end of said rocking lever 66. With this construction it will be seen that when the arm 64 moves to the right, Fig. 12, thereby to move the front 75 needle plate 62 to the right, the bracket 65 which is rigid with the needle plate 62 will act on the pin 166 thereby to swing the rocking lever 66 about its central pivot. This turning movement of the lever 66 will 80 operate through the pin 169 and bracket 68 to move the rear needle plate 63 to the left. The pin-and-slot connections between the rocking lever 66 and the brackets 65 and 85 68 permit of this movement without causing any binding of the parts. Similarly, when the projection 64 is moved to the left, Fig. 12, the front needle plate 62 will be moved to the left, but the rear needle plate will be moved to the right through the connections above described. These needle plates have provided between them a longitudinally-extending slot 69 through which passes the completed fabric when the machine is operated. On the outer surfaces 90 of the needle plates are formed a series of slots in the usual manner for the reception of the needles 70. The needles are of the usual kind used in machines of this class and the hubs 71 project outwardly from the 95 100 slots.

Each needle-lifting plate is provided with a needle-lifting bar 72 which are fastened together and slide upon the needle plates, the front needle-lifting bar being supported upon the upper ends of needle-lifting rods 16 and 17 whereby a vertical reciprocating movement is imparted to the needles. The hubs of the needles rest upon the top of the needle-lifting bars, and a slotted bar 73 is 110 adapted to rest upon said bars to hold the hubs of the needles against displacement, and a retaining strip 74 rests upon said slotted bar and the hubs of the needles, upon 115 which retaining strip is mounted the upper inwardly-extending leg of an inverted L-shaped cap piece 75. Cap 75 is secured to the needle-lifting bars by screws 76.

The threads or yarns are moved from one position to another and properly presented 120 to the needles by means of thread carriers, whose construction and actuating mechanism are described as follows:

The push rod 22 operates two sets of 125 thread carriers, and extends up loosely 130

through an aperture in a bracket 77 on the standard 59 and is connected at its upper end to a cross-head 78. Two cross bars 79 and 80 are centrally mounted on a rod 81 for a pivot. Two link bars 82 and 83 are loosely mounted at their lower ends in the cross-head 78 by a pivot 84, and the other ends are loosely connected with the lower ends of the cross-bars 79 and 80 by pivots 85 and 86, respectively.

At the upper ends of the cross bars 79 and 80, respectively, are pivotally mounted the two spreader bars 99 and 100 of the thread carriers, as seen in Fig. 2. These thread carriers are centrally mounted on the pivot rod 81.

The link bars 82 and 83 together with the cross bars 79 and 80 constitute lazy tongs, which open and close alternately as the push-rod 22 rises and descends.

There are two parallel upright posts 101 and 102 mounted at their lower ends in the bed plate 3 to extend upwardly therefrom.

It is to be understood that the push-rod 23 on the left-hand end of the machine operates a similar set of lazy tongs (not shown). These two sets of lazy tongs spread and close alternately the series of thread carriers.

The thread carriers which guide the thread and deliver it to the needles are composed of side thread carriers designated 103, 104, respectively, and end thread carriers designated 111, 112, respectively. The end thread carriers are situated at each end of the rows of needles and the side thread carriers are those which are situated between the end thread carriers. The side thread carriers are all pivotally mounted on the rod 81 and are arranged in pairs, the thread carriers of each pair being designated 103, 104, respectively, and being placed so that their upper ends extend in opposite directions. With this arrangement the thread carriers will be formed in two rows, the thread carriers 103 having their upper ends projecting toward the front of the machine and the thread carriers 104 having their upper ends projecting toward the rear of the machine. The front set of side thread carriers 103 are connected at their upper ends by a spreader bar 99, whose function is to spread the threads or yarns. In like manner, the rear set of side thread carriers 104 are connected by another spreader bar 100 of similar construction. Spreader bars 99 and 100 have an integral rib 107 which extends into and fits snugly in slots in the upper ends of said thread carriers, respectively, and holds them together. The outer longitudinal edge of each spreader bar is curved or rounded, as shown, to enable the threads to pass smoothly over said edge. Each thread carrier has in its lower end an eye 108 for the loose passage of a thread therethrough.

The push-rod 81 operates the end thread guides and extends up loosely through an aperture in bed plate 3 and is connected at its upper end to the lower outwardly-extending leg of a bell crank lever 109 pivotally mounted upon rod 81. The other leg of the lever 109 extends upwardly and supports one end of an oscillating rod 110, which rod 110 extends parallel with rod 81 and between the out-turned ends of the side thread guides. The end thread guides 111 and 112 (Figs. 10 and 11) are arranged in pairs and are described as follows:

Each pair of these guides is composed of a long member 111 and a short member 112. Member 111 extends upwardly from rod 110 and is supported at its upper end upon a pivot rod 113 mounted in bearings secured to posts 101 and 102, and is provided with a transverse slot 114 through which the rod 81 passes. The short member 112 is pivotally mounted upon the rod 81 and extends upwardly therefrom a short distance, and its upper end is threaded upon the oscillating rod 110, the rod 110 also passing through the member 111. In operation the member 111 being pivoted above and member 112 being pivoted below oscillating rod 110, as said rod is vibrated back and forth, the lower ends of these members will be caused to travel in opposite directions for a purpose hereafter described.

The thread carriers oscillate between and are supported laterally by slays or reeds 115, as shown in Figs. 7 to 10, inclusive. At the top of the posts are mounted brackets 116. A selvage spool or roll 117 is mounted rotatably on a rod 118 which extends between the brackets 116. Two other brackets 217 are secured by set-screws 218 to the posts 101 and 102, respectively. A rod 119 is supported at its ends in the brackets 217. The main roll or beam 120 is loosely mounted on the rod 119 and is held from longitudinal displacement by a spiral spring 220, as shown in Fig. 1.

124 designate two sets of thread guides in the shape of combs through which the thread from the beams pass. These combs are supported upon arms 123 formed on brackets 121 that are adjustably secured to the uprights 102. These brackets also support a rod 125 upon which is loosely mounted a friction roller 126. At one end of the roll 126 is mounted a friction pulley 127 over which passes a friction strap 128, the ends of which are secured to spiral springs. The other ends of these springs are fastened, the one to the bracket 226 secured to the push-rod 16, and the rear one to the frame of the machine or other suitable support. These spiral springs have each a hook at its upper end and each hook is engageable with any one of the adjacent holes in the strap to vary the tension of said strap. 130

These springs draw the strap 128 forcibly down upon the spool or channel of the friction pulley and retard its rotation, so that it turns only when the downward pull of 5 the needles in the knitting operation actuates said roller to deliver the thread therefrom.

The threads, before reaching the needles, are moved and properly presented thereto 10 by the series of side thread carriers 103 and 104 which are arranged in pairs, as shown in Figs. 7 to 9, inclusive, one thread carrier for each thread. In the drawings, Fig. 7 represents the first operation; Fig. 8 the 15 second; and Fig. 9 the third. The travel of one pair of the thread carriers is diagrammatically represented in plan view in Fig. 14, where I indicates a movement of the thread carriers to the front; II a movement 20 to the right; III a movement to the center; IV a movement to the right; V a movement to the front; VI a movement to the left; VII a movement toward the center, and 25 VIII a movement to the left. The two 30 closed ovals indicate the position of the needles, around which the thread make this travel.

In Fig. 15 is a diagrammatic representation of the stitches or loops of thread so laid 35 by the thread carriers around these needles. In the center these threads have a closed loop made by the knitting mechanism as shown. This closed loop is formed at the central position where the converging 40 thread carrier movement VIII and I approach nearest the converging thread carrier movements IV and V.

In Fig. 8 the two thread carriers 103 and 45 104 meet at their lower ends and this is the innermost point in their oscillatory motion. In Fig. 7 the lower end of the thread carrier 103 moves to the front and the lower end of the thread carrier 104 moves to the rear. In Fig. 8 the thread carriers 103 and 104 50 return to their closed or central position, and in Fig. 9 the lower end of the thread carriers move to the position shown in Fig. 7.

It being understood that each set of the 55 side thread guides feed threads or yarns to the needles of one side only and that these two sides are connected or joined together at the ends by the end thread guides as follows:

The movement of one pair of end thread guides is shown at the right-hand side of 60 Fig. 15, from which figure it will be seen that the threads which are controlled by the end thread guides are manipulated so as to 65 be acted upon by the needles of both sets, thus knitting together the two sides of the fabric at the ends thereof.

The threads passing smoothly over the rounded edge of the spreader bars 105 and

106, extend to and through the eyes of the 65 thread carriers to the needles.

The needle movement will be now described in general terms.

There are two kinds of needle movements, one is an alternate upward and downward movement in a vertical plane, and the other is an alternate horizontal movement in 70 said plane.

The front cam shaft 6 in rotating turns with it the cams 12 and 13, which impart a 75 reciprocating movement to the shoes 14 and 15. The push-rods 16 and 17 which extend up from said shoes, are connected at their upper ends (Fig. 13) with the needle-lifting bars 72. Thus the needles have a regular 80 reciprocating vertical movement by reason of the mounting of the hubs of the needles on the needle-lifting bar, as represented in Fig. 7, where it is seen that there are two connected needle-lifting bars and 85 their accessories, one for the front, and one for the back of the machine.

The horizontal reciprocation of the needle bars 62 and 63 and of the needle-lifting bars therewith is caused by the cam 33 on the 90 left-hand end of the rear cam shaft 7, as shown in Fig. 1. This cam shaft gives a movement to the rocker bar 35 which is pivotally mounted on the bracket 34, and this rocking movement is communicated to 95 the needle bar 62 and through the rocking lever 66 to needle plate 63, back and forth in each rotation of said cam shaft, it being understood that as the front needle bar moves to the right the rear needle plate will 100 move to the left and vice versa. The length of each horizontal reciprocation is equal to the distance between two adjacent needles.

As the threads are knitted into the fabric 105 the latter passes from the needles down between the two needle plates through the tape space 69 and is subjected to the stitch-tightening mechanism, as shown in Fig. 7, and presently described, and are wound upon the take-up roll or drum (not shown). 110

The kind of fabric made by this machine cannot be sufficiently close and firm on a knitting machine (in the first or best quality of goods) without the use of a suitable stitch-tightening device. In my machine 115 there is provided a stitch-tightening mechanism which draws each row of stitches as they are formed and are leaving the needles by taking up the slack of the thread. By a combination of cam movements the loops 120 or stitches are closed to any degree required after leaving the needles, and thus the fabric can be made much tighter than has been heretofore possible in machinery of this class. On each rotation of a front cam 125 shaft, the rod 40 is pulled toward the rear of the machine and the threads which pass in front of the two fixed rods 42 and 48

are drawn slightly toward the rear by the rod 40, operated by the lever 36 and the cam 24, as already described.

The threads or yarns are fed to the needles by the thread carriers. The needles descend and the rod 40 moves forward toward the operator, thus releasing the tension on the fabric and causing the loops or stitches to hang loose as the needles begin to form new loops. The friction strap 125 on the end of the roller 123 gets tighter as the needles descend, putting in more and more tension on the yarns or threads as the needle bar descends. As the new loops are formed, and the old loops are leaving the needles (the tension on the yarn being tight and the old loops loose), the needles draw on the line of least resistance and draw all the slack out of the loops which are leaving the needles, before drawing on the yarn which is under tension on the main rollers. Then as the needles move to the bottom and new loops are formed and the needles begin to rise, the rod 40 moves backward again and puts tension on the fabric. As the needles rise for the next stitch the friction strap 125 being connected to the bracket 126 is eased off and allows the needles to rise, thus forming a compact fabric and allowing the thread carriers to perform the necessary movements without excessive strain on the threads or yarns.

It is of great importance that the tension of the yarns or threads which pass from the main roller to the needles should be equalized and made constant. For this purpose the friction roller 125 is used and gives a complete control of the tension on the threads or yarns. These threads after leaving the main roller are wound once around the friction roller and the fact that the main roller is full, or partially full, makes no difference to this tension. Without this device the tension would vary continually, and the tension would increase from the time when the main roller was put up full until it was empty because as the roll of yarn or thread becomes smaller the leverage thereof is correspondingly lessened and the pull or draft upon the threads becomes greater and greater until finally the threads or yarns would break from too much tension. In my device this tension is always the same because the friction roller has only one winding of each thread thereon and the diameter is always the same and the threads are delivered therefrom to the needles under a constant tension.

As the needles rise the rod 40 takes up the fabric. If the fabric were not so held the needles would pull it up. As the needles descend the rod 40 moves forward and releases the fabric, and at the same time the

friction strap 125 is beginning to tighten. The tension of the spiral springs on the ends of the strap 125 may be adjusted by means of holes in said strap.

In the knitting process the needle latches are closed by the descent of the needle stem 70 through the thread loop, which has just been laid on the needle by the thread carriers, and when the loop has been knit into the fabric and the needle has been freed therefrom the rise of the needle causes the threads from the thread carriers to engage the needle latch and move it downward into its open position, as seen in Figs. 7 and 9.

The oscillating movement of the side thread carriers is caused by the cams 18 and 19 on the front cam shaft 6, which cam operating the cam shoes 20 and 21 cause the push-rods 22 and 23 alternately to move up and down. In moving up this push-rod opens the lazy tongs (made up of the pivotally connected bars 77, 80, 82 and 83,) thus opening the spreader bars to their widest extent, but in moving down the push-rods 22 and 23 close the lazy tongs.

The oscillating movement of the end thread carriers is caused by the cams 27 and 28 which cams operating shoes 29 and 30 causes the push-rods 31 and 32 to move alternately up and down, thus rocking the bell crank lever 109 and vibrating the rod 110 to open and close the end guides as heretofore described.

The periodical rise and descent of the needles are caused by the cams 12 and 13 of the front cam shaft 6 which give a 100 vertical reciprocating movement by means of the cam shoes 14 and 15 on said cams, respectively, and this movement is communicated by the push-rods 16 and 17 to the needle-lifting bars.

The hubs 71 of the needles 70 rest upon the needle-lifting bars 72 and are held thereto by the comb bars 73 and covering strips 74. Thus the needles rise and fall periodically in the ordinary well-known manner.

It has been stated that the front cam shaft 6 rotates twice while the rear cam shaft 7, geared thereto, rotates once. It is also apparent that said shafts rotate in opposite directions. It will be seen from Fig. 6 that cams 27 and 28 are of such configuration peripherally that push-rods 31 and 32 will have two successive upward movements and then two successive downward movements during each revolution of shaft 7. It will also be seen from Fig. 2 that cams 18 and 19 are so formed that push-rods 22 and 23 will move up and down once during each revolution of shaft 6, and that cams 12 and 13 will move rods 16 and 17 up and down once for each revolution of shaft 6.

The stitch-tightening device cooperates with the friction take-up rolls 53 and 55. A

pulley 46 on the front cam shaft 6 causes a band to travel from said pulley over pulleys 44 and 45 to the pulley 48. The pulley 48, being tight on the shaft 49, rotates said shaft which turns with its worm 50 to operate the worm gear 52. This worm gear being fast on the shaft on which the rear take-up roll 53 is secured, turns said roll, which in turn rotates roll 55 through its connected gearings. The knit fabric is drawn by these rolls and passes to the take-up reel or drum, not shown.

The stitch tightener operates after each row of stitches has been formed. The cam 15 24 on shaft 6 is so timed with relation to the cams 12 and 13 on said shaft and also with the pulley 46 on shaft 6 and the pulley 48 on the shaft 49, that the stitch is tightened when the needles reach their 20 lowest position.

A variety of other stitches can be made by changing the movements and relations of the needles with respect to the oscillating thread carriers and thus the pattern of the 25 knit fabric can be changed or varied as desired.

The take-up d. am, not shown, may be operated in any desired manner, but is preferably operated as shown and described in 30 my application filed February 7, 1913, Se. No. 746,828.

It will be understood that while I have described and shown my preferred form of construction and operation, I do not limit 35 myself thereto but may vary the same if desired.

I claim:

1. In a knitting machine, the combination 40 of a set of thread carriers arranged parallel to one another and adapted to oscillate in unison upon a pivot rod common to all, two sets of knitting needles extending in parallel rows beneath the lower ends of said thread carriers, means for giving to all said needles 45 simultaneously vertical linear movements up and down, means for giving to said rows of needles simultaneously horizontal linear movements in opposite directions alternately from side to side, and a thread supply for 50 said needles.

2. In a knitting machine, the combination 55 of a main shaft, a series of oscillatory thread carriers arranged in a straight row in pairs side by side, a pivotal support for said thread carriers, a plurality of knitting needles arranged in two rows beneath said thread carriers, a thread roll adapted to deliver thread to said carriers and by them to 60 said needles, two needle bars supporting said needles vertically and movable horizontally in a straight line alternately from right to left in opposite directions, two needle-lifting bars engaging said needles, a take-up roll receiving the finished fabric, operated by devices intermediate said shaft

and roll, mechanism operated by said shaft and imparting to said needle bar said horizontal reciprocations, mechanism operated by said shaft and imparting an oscillatory movement to the thread carriers, and mechanism operated by said shaft and imparting a vertical reciprocation to the needle-lifting bars.

3. In a knitting machine, the combination 7 of a main shaft, a plurality of pivotally-mounted thread carriers arranged in pairs side by side in a straight row, each pair of thread carriers comprising two metallic strips connected loosely by a pivot and thereby capable of moving upon each other 8 to open or close, a plurality of knitting needles arranged in two straight rows beneath said thread carriers, a thread roll adapted to deliver thread to each of said thread carriers and by them to said needles, two needle bars upon which the needles are supported vertically, two needle-lifting bars engaging said needles, mechanism intermediate said shaft and thread carriers adapted 9 to impart from the shaft oscillatory movements to the thread carriers, mechanism intermediate the shaft and needle bars adapted to impart from the shaft a horizontal reciprocation to the needle bars in opposite 91 directions relatively to each other, mechanism intermediate said shaft and needle-lifting bars adapted to impart from said shaft a vertical reciprocation to said needle-lifting bars.

4. In a knitting machine, a plurality of 10 knitting needles suitably mounted in two parallel rows, a thread supply for each of said rows of needles, and a thread supply 10 adapted to supply threads alternately to the opposite needles at the ends of each of said rows of needles whereby the fabric knitted by said rows of needles is connected together at the ends thereof, means to vary the tension on the threads in timed relation to the 11 operation of the needles and to draw tight the stitches as they are shed from the needles.

5. In a knitting machine, the combination 11 of a main shaft, a plurality of pairs of obtuse-angled plates, the plates of each pair being placed side by side so that when their lower ends overlie one another the upper ends flare outwardly, a pivot on which said plates are loosely mounted, an eye in each 12 plate at the bottom thereof, a hooked needle for each plate, said needles being arranged in two rows, a thread supply delivering a thread to each of said plates through the eye thereof to a position where the hook 125 of a needle is engageable therewith, mechanism operated by the shaft and adapted to lift the needles into proximity with the pairs of thread carriers and between them when their lower ends are in an open posi- 130

- tion angularly, means operated by the shaft and adapted to lower said needles into engagement with the threads, means operated by the shaft and adapted to move the needles periodically in a horizontal plane at right angles with said needle lifting movement alternately right and left in opposite directions to each other, and means operated by the shaft adapted alternately and periodically to open and close the lower ends of said thread carriers.
6. In a knitting machine, a plurality of needles suitably mounted in two rows, means to impart a horizontal reciprocation to said rows of needles in opposite directions relatively to each other, means to impart to all of said needles a periodical vertical reciprocating movement, a thread supply for said needles, tensioning means for said thread supply whereby said thread supply is alternately tensioned and released during its passage to the needles, and means to draw tight the stitches formed by said needles upon their leaving the same.
10. In a knitting machine, the combination of two rows of needles suitably mounted, supplemental knitting mechanism for said needles adapted to cause all said needles to perform knitting movements simultaneously; means adapted to impart a horizontal reciprocating movement to said rows of needles, in opposite directions relatively to each other, a rotatably-mounted main thread roller adapted to have wound thereon a thread supply for said needles, a revolvably-mounted tension roller intermediate the main thread roller and the needles around which roller each thread from said thread supply is wound one turn during its passage to the needles, a friction strap having elastic ends passing over the tension roller, one of said ends being connected to the vertical reciprocating means of the knitting mechanism, and the other end being connected to a stationary part of the machine whereby said strap is alternately tightened or released when the machine is operated.
15. In a knitting machine, a plurality of needles suitably mounted in two rows, means to impart a horizontal reciprocating movement to said rows of needles in opposite directions relatively to each other, means adapted to impart to said needles a periodical vertical reciprocating movement simultaneously, a thread supply for said needles, tensioning means for said thread supply between said thread supply and needles adapted to alternately retard and release said threads upon their passage to the needles upon the operation of the vertically-reciprocating means.
9. In a knitting machine, a plurality of needles suitably mounted in two straight rows and spaced apart, means to impart a horizontal reciprocating movement to said rows of needles relatively to each other, means to impart to all of said needles a periodical vertical reciprocating movement simultaneously, a thread supply for said needles, tensioning means for said thread supply between said thread supply and needles adapted to alternately retard or release said threads on their passage to the needles upon the operation of the vertically-reciprocating means, take-up mechanism, and means between said take-up mechanism and needles adapted to draw tight the stitches formed by said needles upon their leaving the same.
20. In a knitting machine, the combination of a plurality of sets of thread guides arranged parallel to each other and adapted to oscillate in unison upon a pivot rod common to all, a plurality of sets of selvage guides arranged at intervals between said first-mentioned guides and adapted to oscillate therewith, two sets of knitting needles extending in parallel rows beneath the lower ends of said thread carriers, means for giving to all said needles simultaneously vertical reciprocating movements, means for reciprocating said rows of needles horizontally in opposite directions relatively to each other, means to oscillate said thread guides, means to oscillate said selvage guides, and a thread supply for said needles.
25. In a knitting machine, a plurality of knitting needles arranged in two rows parallel to each other, a series of oscillating thread carriers arranged in a straight row, there being one set of thread carriers for each row of said needles, means to impart to all said needles simultaneously vertical reciprocating movements, means to impart to each row of said needles a periodical horizontal reciprocating movement opposite to each other, a plurality of sets of selvage thread carriers arranged at intervals in the series of thread carriers, means for oscillating said thread carriers, means for oscillating said selvage thread carriers, a thread supply for said thread carriers, and a stitch-tightening device adapted to draw tight the stitches formed by said needles as they are leaving the same.
30. In witness that I claim the foregoing I have hereunto subscribed my name this 11th day of December, 1914.
- JOHN WATERFIELD.
